UNITED STATES PATENT OFFICE.

WILLIAM F. PAGEL, OF SYCAMORE, ILLINOIS.

WASHING MACHINE.

1,402,372.

Specification of Letters Patent. Patented Jan. 3, 1922.

Application filed April 26, 1920. Serial No. 376,446.

To all whom it may concern:

Be it known that I, WILLIAM F. PAGEL, a citizen of the United States, and resident of Sycamore, in the county of De Kalb and

5 State of Illinois, have invented certain new and useful Improvements in Washing Machines, of which the following is a specification.

10 My invention relates to improvements in washing machines and has special reference to machines of the plunger type.

15 The object of my invention is to provide a machine which shall wash clothes cleaner, with less wear, and more quickly than is accomplished with the machines now in use. A further object of my invention is to provide a washing machine in which there shall be no necessity of alternating the direction of operation from time to time as in the

20 barrel type of machine and which shall automatically turn the clothes over in different directions to the end that every part and portion of the clothes shall be subjected directly to the suction cleaning action.

25 Instead of reciprocating a plunger up and down into and out of the vessel in which the clothes and water are placed, I lift the clothes up through the water and plunge them down into the water. The lifting produces the suction cleaning action and the plunging produces the turning and changing action.

30 I provide a continuous up and down movement of the basket or container in which the clothes are carried. In the lifting movement the water flows out and in fact is drawn through the clothes and through holes in the container into the bottom of the tub and on the downward movement the water 35 is forced up into the basket or container from below lifting and loosening the clothes, turning them over and around to present a different portion of the clothes to the suction action of the next lifting of the basket. One 40 important feature of my invention resides in the means which I employ for causing an alternate circulation and overturning of the clothes upon successive or alternate down stroke.

45 My invention resides in a washing machine having a closed container adapted to hold the water movable up and down in a tub or casing, and having means for permitting the water to flow out through perforations in the side walls of the container 50 on the up stroke and means for causing the

water to flow up through suitable openings in the bottom of the container on the down stroke for lifting, turning and changing the clothes.

60

My invention will be more readily understood by reference to the accompanying drawings forming part of this specification, and in which:—

Figure 1 is a fragmentary vertical central 65 section of a washing machine embodying my invention;

Figure 2 is a horizontal section on the line 2—2 of Figure 1;

Figure 3 is a fragmentary vertical section 70 on the line 3—3 of Figure 2;

Figures 4 to 7 inclusive are fragmentary 75 diagrammatic views illustrating the operation and the several positions of the rotating valve.

In said drawings 1 is a tub or casing, preferably in the form of a vertical cylinder, having an integral bottom 2 and a removable cover 3. The casing is supported in vertical position and at a suitable height by a stand 4 having a ring member 5 in which the bottom of the casing or tub 1 fits and legs 6 for raising the machine above the floor to provide space beneath the casing for the gas burner 7. The gas burner is supported upon 85 a bracket 8 having strap hangers 9 at its ends provided with outturned supporting flanges 10 at their upper ends received in the inner edge of the ring member 5.

In the tub or casing 1, I arrange a metal 90 basket or clothes container 11 having a perforated side wall 12 and a substantially solid bottom 13. The basket is of considerable less height than the tub and is adapted to be reciprocated up and down within the tub 95 to wash the clothes.

The body of the container is smaller than the casing to provide a circumferential chamber or space 14 surrounding the container. This space is closed at its upper end 100 by a flange 15 at the upper edge of the container, which substantially fits the tub and a similar flange 16 at its lower end which also substantially fits the tub. The horizontal flange 16 is provided with a number of openings 17 through which the water can flow down as the container is raised and these openings are closed by check valves 18 which close upwardly against the flange 17 when the container is forced down. These valves 110 are normally held closed by springs 19 arranged between projections 20 on the side

of the container through which the valve stems 21 project and heads 22 on the upper ends of the valve stems.

For reciprocating the container I provide 5 a vertically oscillating shaft or yoke 23 mounted in a bearing 24 on the side of the tub and being curved to conform with the curvature of the tub provided with aligned pivots 23' at diametrically opposite points 10 relative to the tub. Links 25 rise from the pivots of the shaft 23 and pivotally engage the upper ends 26 of reach rods 27 arranged within the tub and whose lower ends 28 are rigidly secured to the flange 16 of the container.

The shaft 23 is swung up and down by any suitable mechanism, shown diagrammatically by the gear wheel 29, carrying a crank pin 30 which is connected to the one end of 20 the shaft 23 by a link 31. The gear wheel is rotated by any suitable mechanism such as the pinion 32 mounted on a shaft 33 and carrying a belt pulley 34.

In the center of the bottom 13 of the container I provide an opening 35 large enough 25 to admit the water into the container as the container descends. To prevent the clothes falling through the opening on the up stroke I place bars or wires 36 across the opening 35. I preferably form the bottom 13 upwardly toward the center opening as shown so that the water will flow up into the opening 35 without undue friction.

In the operation of the machine as so far 35 described the clothes are placed in the container 11 and the cover 3 is placed in position. Water or suds are placed in the tub to a suitable depth. The container is then reciprocated up and down within the casing. 40 On the up stroke the water flows out through the holes 12 in the side wall 11 of the container and down through the openings 17 in the flange 16 thus producing the suction action which carries the dirt out of the clothes. 45 On the down stroke the water is prevented from rising through the openings 17 by the valves 18 and it is forced to rise through the central opening 35 thus lifting the clothes and turning them over in the container 11. 50 The dirt and other particles removed settles down in the bottom of the casing 1 and is not disturbed. During this process of washing, the contents of the washer can be heated by means of the large gas burner 7. It is to be 55 noted that as there is no space occupied below the casing by motors or other devices the gas burner can be large enough to rapidly heat the contents of the washer and to maintain them hot during the washing operation.

In addition to the clothes turning effect of the stream of water rising through the central opening 35, I have found that it is desirable to provide other and additional 65 means for disturbing the clothes in their

position and turning them over and I have provided means for automatically causing the clothes and the water in the container to rotate within the container in one direction on one down stroke and in the opposite direction on the next successive down stroke of the container. This means consists of a water inlet 38 through the bottom 13 of the container communicating at its two sides with arcuate passages 39 and 40. I 70 control the flow of the water into the container through the passage 38 and the connecting passages 39 and 40 by means of a rotating valve 41 which alternately delivers the water from the passage 38 to the passages 75 39 and 40 on successive down strokes of the container so that the stream entering the container upon one down stroke rotates the clothes and the water therein in one direction and on the successive down stroke rotates the clothes and the water therein in the opposite direction. This valve 41 is cylindrical and has two passages 42 and 43 therein, one of which at a time communicates with the passage 38 and with one of the passages 80 39 or 40 as the case may be. The passage 42 as shown in Figure 3 is connecting the inlet 38 with the passage 39 and as the valve is rotated this communication is cut off and upon the next down stroke the passage 38 85 is connected with the other passage 40 as illustrated in dotted lines in Figure 6.

For rotating the valve 41 to produce the alternate communication of the passages 39 and 40 with the inlet 38 upon successive 100 down strokes of the container I provide a four armed star wheel 44 carried upon the outer end of the valve and arranged close to the wall of the casing and having arms 45, 46, 47, and 48.

In Figure 4 I have shown the valve 41 and the star wheel 44 in full lines as shown in Figure 3; that is, with the inlet 38 in communication with the passage 39. The container is shown as descending and ready to move the valve to shut off communication between the inlet 38 and the passage 39. This is accomplished by means of a stop pin 49 mounted on the wall of the casing in the path of the arm 45 of the star wheel 44 and adapted to rotate the star wheel through substantially one eighth of a turn to the dotted position shown in Figure 4 as the container reaches the lower limit of its movement. This dotted position of the star wheel and valve is shown in full lines in Figure 5 wherein the inlet 38 is cut off from communication with both of the passages 39 and 40 and the valve remains in this position during the up stroke of the container. 110 It is turned to open communication between the inlet 38 and the passage 40 at the upper limit of the movement of the container by a stop pin 50 also mounted on the wall of the casing in the path of the arm 46, which 115 120 125 130

is adjacent to the arm 45 which has just been moved by the stop pin 49. As the container rises the star wheel contacts with the pin 50 and rotates the valve to open communication between the inlet 38 and the passage 40 as illustrated in Figure 6 and this communication is maintained during the next down stroke of the container at which time the next successive arm of the star 10 wheel contacts with the stop pin 49 and again rotates the valve through an eighth of a revolution shutting off communication between the inlet 38 and the passage 40 and closing communication between the inlet 38 15 and both of the passages during the next successive up stroke of the container at the end of which the star wheel is again rotated through one eighth of a turn again opening communication between the inlet 38 and the 20 passage 39 for the next successive down stroke.

It should be understood that many other devices for controlling the valve and communicating passages could be devised to accomplish the results of causing an inflow of the water through the bottom or other wall of the container on the down stroke of the container and alternating the direction of flow on successive down strokes to cause the 25 clothes and water to rotate in one direction upon one down stroke and in the opposite direction on the next successive down stroke.

I have found that the lifting of the clothes by the central stream and the rotating of the 30 clothes and water by the tangential streams operating in opposite directions on successive down strokes causes a satisfactory overturning and changing of the position of the clothes in the container and facilitates the 35 rapid washing and cleansing thereof.

As many modifications of my invention will readily suggest themselves to one skilled in the art I do not limit or confine my invention to the specific structures herein 40 shown and described.

I claim:

1. In a washing machine of the kind described, a casing for water, a clothes container substantially fitting within the casing, 50 and movable up and down therein, the container having perforated side walls through which the water flows out during the up stroke and having an opening in its bottom through which the water flows up on the 55 down stroke, and means preventing the water flowing into the container through the holes in the side walls during the down stroke, substantially as described.

2. In a washing machine of the kind described, a tub, a clothes container movable up and down in the tub, the container being smaller in horizontal dimensions than the 60 tub, means at the upper edge of the container and a flange at the lower edge of the 65 container for engaging the tub to guide the

container in its up and down movements, the container having perforations in its side walls, said flange provided with openings through which the water can flow on the up stroke of the container, valves for closing 70 said openings on the down stroke of the container, the bottom of the container having valve controlled openings to permit the water to rise into the container on the down stroke, substantially as described. 75

3. In a washing machine of the kind described, a tub, a clothes container movable up and down in the tub, the container being smaller in horizontal dimensions than the tub, means at the upper edge of the container and a flange at the lower edge of the container for engaging the tub to guide the container in its up and down movements, the container having perforations in its side walls, said flange provided with openings 80 through which the water can flow on the up stroke of the container, valves for closing said openings on the down stroke of the container, the bottom of the container having an opening through which the water is 85 forced up on the down stroke for lifting and turning the clothes, substantially as described. 90

4. In a washing machine of the kind described, a casing adapted to contain water, 95 a clothes container movable up and down in the casing, the container being substantially circular in horizontal cross section and the wall of the container provided with an opening through which the water enters on the down stroke, said opening adapted to direct the water substantially tangentially to the wall of the container to cause the clothes and water to rotate in the container, substantially as described. 100

5. In a washing machine of the kind described, a casing adapted to contain water, a clothes container movable up and down in the casing, the wall of the lower part of the container being provided with oppositely 110 directed water inlet passages and means for alternating the flow of water through said passages, substantially as described.

6. In a washing machine of the kind described, a casing adapted to contain water, 115 a clothes container movable up and down in the casing, the wall of the lower part of the container provided with two oppositely directed water inlet passages and means for alternating the flow of water through the 120 passages on successive down strokes to cause the clothes and water in the container to alternately rotate in opposite directions, substantially as described.

7. In a washing machine of the kind described, a casing adapted to contain water, a clothes container movable up and down in the casing, the bottom of the container provided with two oppositely directed water inlet passages, valve means controlling said 130

passages, and means for operating said valve means for alternating the direction of flow of the water through the passages on successive down strokes, substantially as described.

8. In a washing machine of the kind described, a casing adapted to contain water, a clothes container movable up and down in the casing, the bottom of the container provided with two oppositely directed passages, a valve controlling said passages, and means for operating the valve to direct the water through one of the passages on one down stroke and through the other passage on the successive down stroke, substantially as described.

9. A washing machine of the kind described comprising a circular tub or casing closed at its bottom, a circular basket or container adapted to be reciprocated up and down in the tub in the lower part thereof, rods rigid with the container projecting up through the top of the casing for reciprocating the container, means engaging the upper ends of the rods for moving the container up and down, the container being smaller in diameter than the tub to provide a chamber around the container, flanges at the upper and lower edges of the container for engaging the tub to guide the container, the container having perforations in its side walls opening into said chamber, the lower of said flanges having openings to permit the water to flow down as the container is raised, check valves for closing said openings to prevent the water flowing up when the container descends, the bottom of the container provided with oppositely directed openings for directing streams into the container to cause the water and clothes therein to rotate, and means for alternating the flow of water through the oppositely directed openings, substantially as described.

10. In a washing machine of the kind described, a clothes container adapted to be reciprocated up and down in the machine and to rise clear of the water on the up stroke, the container provided with laterally extending passages in its bottom through which the water flows on the down stroke for rotating the clothes in the container and means for directing the flow of water into the container in opposite directions on alternate down strokes, substantially as described.

11. In a washing machine of the kind described, a casing closed at its bottom, a clothes container within the casing movable up and down therein, vertical rods rigid with the container and rising out of the tub for moving the container up and down, depending links pivotally connected at their upper ends to the upper ends of said rods, a yoke rotatably mounted on the tub at its middle portion and having its ends pivotally connected to the lower ends of the links, and means for oscillating the yoke to move the container up and down, substantially as described.

Signed at Chicago, Illinois, this 14th day of April, 1920.

WILLIAM F. PAGEL.
